UNITED STATES PATENT OFFICE.

JOSEPH LEE ROUSSEAU, OF BROOKLYN, NEW YORK, ASSIGNOR TO MERGENTHALER LINOTYPE COMPANY, A CORPORATION OF NEW YORK.

JUSTIFYING SPACER OR SPACE BAND.

Application filed October 4, 1926. Serial No. 139,310.

This invention relates to justifying spacers or spacebands, such as are used in commercial linotype machines for the justification of a composed matrix line preparatory to the 5 slug casting operation. These spacebands consist each of a short wedge-shaped member which is locked or held stationarily in the line, and a longer relatively movable wedge-shaped member which extends below the line, the two members being connected together by a sliding joint so that the longer one may be thrust upwardly through the line to expand or elongate the same in effecting its justification. In the course of composition, 10 the space bands are released from their storage magazine above the line and drop vertically in front of a rapidly rotating star wheel, or pusher, which acts to advance the line progressively toward the left as composition proceeds. As the spacebands enter the line, the lower ends are caught by the star wheel and thrown violently against the preceding matrix in displacing it to permit the spaceband to descend to its proper position 15 in the line. As a result, the thin side walls of certain matrices are frequently caved in or otherwise damaged, giving rise to the production of imperfect type bars and causing much annoyance and delay in locating the damaged matrices for replacement. In 20 overcoming these difficulties, it is proposed, according to the present invention, to change the ordinary form of the spacebands so that their lower ends will avoid contact with the 25 side walls of the matrices during the composition of the line. To this end, the longer wedge-shaped member of the spaceband, in the preferred embodiment illustrated, is provided at its lower end with a cut or recess 30 which is so formed and located that the desired result is obtained without impairing the strength and durability of the spaceband.

Referring to the drawings:

Fig. 1 is a front view of the assembling mechanism of a linotype machine illustrating the manner in which the spacebands enter the composed line;

Fig. 2 is a rear view on an enlarged scale showing the improved spaceband in the act 50 of entering the line between the star wheel and the matrix which precedes it;

Fig. 3 is a horizontal section taken on the line 3—3 of Fig. 2;

Fig. 4 is a detail perspective view of the 55 improved spaceband; and

Fig. 5 is a perspective view of an ordinary linotype matrix.

The improved spaceband (see Fig. 4) comprises two wedge-shaped members A and A¹ of different lengths, whose outer faces are straight and whose inner faces are inclined at the same angle so that the outer faces will remain parallel at all times. The shorter member A is provided at its upper end with projecting ears a for supporting and holding it stationary during justification, and on its inclined face with a pair of tongues or guides A² which are undercut on their inner edges and arranged in slots A³ formed in the longer member A¹. This longer member presents two marginal bars A⁴ and an intermediate centrally located bar A⁵, the latter being beveled on its opposite edges to fit the undercut edges of the tongues A². There is thus provided between the two 60 wedge-shaped members A, A¹, a sliding joint or connection which serves to hold them in contacting relation and permits the longer member A¹ to be shoved upwardly through the line of matrices X in performing the 65 justifying action. The thick lower end portion of the member A¹ is beveled or rounded on its outer face at A⁶ and has its edges tapered inwardly to facilitate the entrance of the spaceband into the composed line and to reduce wear on the parts. So far as described, the spaceband is of ordinary construction and well known to those skilled in the art.

The characteristic and distinguishing feature of the present invention lies in recessing or cutting away the lower end of the member A¹ as at A⁷, the advantages of which improvement will best be understood from a general description of the manner in which the spaceband is introduced into the line during composition. As shown in Fig. 1, the spacebands are stored in a magazine B, which is arranged directly above the assembler elevator C, and are released singly by 90 an escapement (not shown) under the control of a finger key D acting through the regular keyboard power mechanism and the pivoted rocking lever D¹. The released bands drop by gravity through a chute B¹ 105 and enter the line, at a slight inclination, between a rotary star wheel E and the matrix previously composed in line. The star wheel E acts upon the matrices and spacebands alike, i. e. to assist them in reaching 110

an upright position within the assembler C and to push them successively against the line, which is moved bodily forward step by step according to the thickness of the element last added to the line. It will be noted by reference to Fig. 2, which shows a normal relation of the parts, that the upper characters α of the matrices X are disposed approximately on a level with the axis of the star wheel E, so that from the time the thick lower end of a descending spaceband, if constructed as ordinarily, reaches the position shown until it passes below said level the character side walls α^1 of the preceding matrix is liable to damage by the thumping of that portion of the spaceband caused by the rapid rotation of the star wheel. This condition is even more pronounced when the matrix is assembled at the "upper level" (see dotted lines in Fig. 2) because, then, the side walls of both characters are subjected to such pounding on the spaceband in entering the line. As a matter of fact, the upper character, being above the horizontal center line of the star wheel, is more liable to damage in the latter case, since the vibrations of the spaceband as it engages the star wheel are obviously much greater than when it has reached the full line position indicated. The cut or recess A⁷ before mentioned obviates these difficulties by affording a clearance between the character side walls of the matrix and the lower end of the descending spaceband during its short period of instability in entering the composed line. It should be understood that while the notch A⁷, as shown herein, is of a peculiar tapered form, it might be extended upwardly along the inner face of the band or otherwise modified and still function in the required manner. The present form, however, is preferred since it fully serves the purpose for which it was intended without affecting the strength of the member A¹ or changing the angle of the beveled face A⁶. This angle should be a complement of the angle assumed by the bands as they escape from the chute B¹, so as to conform to the exposed vertical face of the preceding matrix and thus ease the action of the parts.

The invention is of course applicable to other forms of spacebands, the one shown being only one of several forms now in commercial use.

Having thus described my invention, its construction and its mode of operation, what I claim and desire to secure by Letters Patent of the United States, is as follows:

1. In a linotype machine equipped with

circulating matrices, means for assembling the matrices in line, and a series of justifying spacers arranged to enter the line from above, said spacers being cut away at their lower ends so as to avoid contact with the side walls of the matrix characters as they enter the line.

2. In a linotype machine equipped with circulating matrices, means for assembling the matrices in line, and a series of justifying spacers arranged to enter the line from above, said spacers having their lower end portions beveled and formed with cuts or recesses to avoid contact with the side walls of the matrix characters as they enter the line.

3. A justifying spaceband adapted to be composed in line with linotype matrices and comprising a movable slotted wedge-shaped member and a relatively stationary cooperating wedge-shaped member slidably connected thereto, the lower end portion of the movable member being formed with a cut or recess adapted to avoid contact with the side walls of the matrix characters as the spaceband enters the line, for the purpose described.

4. A justifying spaceband adapted to be composed in line with linotype matrices and comprising a movable slotted wedge-shaped member and a relatively stationary cooperating wedge-shaped member slidably connected thereto, the lower end portion of the movable member being reduced in width and thickness to facilitate its entrance into the line and cut away to avoid contact with the side walls of the matrix characters.

5. A justifying spaceband adapted to be composed in line with linotype matrices and comprising a movable slotted wedge-shaped member and a relatively stationary cooperating wedge-shaped member slidably connected thereto, the lower end portion of the movable member being beveled on one side face to facilitate the entrance of the spaceband into the line, and said beveled face being formed with a cut or recess to avoid contact with the side walls of the matrix characters.

6. The justifying spaceband comprising the movable member A¹ and the relatively stationary member A, the lower end portion of said movable member being formed with the beveled side face A⁶, and the clearance cut or recess A⁷.

In testimony whereof, I have affixed my signature hereto.

JOSEPH LEE ROUSSEAU.
